PORCH TRELLIS OR SIMILAR ARTICLE

Ernest Meierjohan, Cincinnati, Ohio

Application August 16, 1957, Serial No. 47,402

Term of patent 14 years

(Cl. D54—2)

Fig. 1 is a front elevational view of a porch trellis or similar article, showing my new design.

Fig. 2 is an enlarged view of the top portion of Fig. 1.

Fig. 3 is an enlarged transverse sectional view taken on line 3—3 of Fig. 1.

The essential features of my design reside in the portions shown in full lines.

I claim:

The ornamental design for a porch trellis or similar article, as shown and described.
